US00D951681S

(12) **United States Design Patent** (10) **Patent No.:** **US D951,681 S**
(45) **Date of Patent:** **** May 17, 2022**

(54) **WORKSTATION**

(71) Applicant: **NINGBO TUOTUO RIVER DESIGN COMPANY**, Zhejiang (CN)

(72) Inventor: **Xiaodong You**, Ningbo (CN)

(73) Assignee: **NINGBO TUOTUO RIVER DESIGN COMPANY**, Zhejiang (CN)

(**) Term: **15 Years**

(21) Appl. No.: **29/747,772**

(22) Filed: **Aug. 25, 2020**

(51) LOC (13) Cl. **06-03**

(52) U.S. Cl.

USPC **D6/655.21**; D6/654.23; D6/655

(58) **Field of Classification Search**

(57) **CLAIM**

The ornamental design for a workstation, as shown and described.

DESCRIPTION

FIG. 1 is a front perspective view of a workstation embodying my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 bottom thereof.

1 Claim, 8 Drawing Sheets
